UNITED STATES PATENT OFFICE

150,325

DESIGN FOR AN ASH RECEIVER

John B. Tenczar, Wallingford, Conn.

Application April 9, 1946, Serial No. 128,403

Term of patent 14 years

(Cl. D85—2)

To all whom it may concern:

Be it known that I, John B. Tenczar, a citizen of the United States, residing at Wallingford, in the county of New Haven and State of Connecticut, have invented a new, original, and ornamental Design for an Ash Receiver, of which the following is a specification, reference being had to the accompanying drawing, forming part thereof.

The figure on the drawing is a perspective view of an ash receiver showing my new design.

My new and ornamental design is characterized by a cup-shaped member simulating the head-end of a large cartridge-casing in which is mounted the lower portion of a vertical ring and through the upper portion of which latter projects the bullet-end of a relatively-small cartridge having its lower end substantially seated against the lower portion of the said ring.

I claim:

The ornamental design for an ash receiver, substantially as shown and described.

JOHN B. TENCZAR.
